(57) **CLAIM**

The ornamental design for a mullion mount, as shown and described.

DESCRIPTION

FIG. 1 shows a front perspective view of a mullion mount, showing the inventor's new design;

FIG. 2 shows a front elevation view thereof;

FIG. 3 shows a rear elevation view thereof;

FIG. 4 shows a left elevation view thereof;

FIG. 5 shows a top plan view thereof;

FIG. 6 shows a bottom plan view thereof;

FIG. 7 shows a front elevation view thereof having an interface device inserted therein;

FIG. 8 shows a top plan view thereof having an interface device inserted therein; and,

FIG. 9 shows a front elevation view thereof having an interface device inserted therein and attached at an end thereof to a side of a mullion.

The broken line portion of the figure drawings is included to show unclaimed subject matter only and forms no part of the claimed design.

1 Claim, 9 Drawing Sheets
